HENRY W. MATALENE, OF BOSTON, MASSACHUSETTS.

STEM-WINDING WATCH.

No. 918,757.

Specification of Letters Patent.

Patented April 20, 1909.

Application filed June 25, 1908. Serial No. 440,217.

To all whom it may concern:

Be it known that I, HENRY W. MATALENE, a citizen of the United States, and a resident of Boston, in the county of Suffolk and State 5 of Massachusetts, have invented certain new and useful Improvements in Stem-Winding Watches, of which the following is a specification.

This invention, while applicable to stem-winding watches in general, is particularly adapted for watches which are designed to be suspended on a neck chain or chatelaine pin secured to the person of the wearer, being intended to provide a stem-winding 10 watch of this character which, when suspended with the back of its case outermost, will have the external appearance of a locket. To this end my invention is characterized by the omission of the usual pendant, crown 15 and bow, and by the employment, for suspending the watch, of means attached to the winding stem, and so located that in a watch containing my improvements the only parts which project and are visible above the 20 watch case, when the watch is suspended, are the outer or exposed portions of the suspending means which are attached to the winding stem and which include, by preference, a terminal portion located within the 25 rim of the watch case and a ring passing through an eye on the outer end of said terminal portion and adapted for suspension on a chain or chatelaine pin, so that the back 30 side of the watch presents the same external 35 appearance as a locket. In connection with this arrangement I provide means for preventing outward movement of the winding stem when the watch is suspended, and in case my improvements are embodied in a 40 stem-winding watch in which, in order to set the watch, the stem has to be pulled outward, the construction is such that while the outward movement of the winding stem is resisted under normal conditions, such outward 45 movement may readily be provided for when desired, provision being made, in all cases, for the rotational movement of the stem by which the watch is wound.

Referring to the drawings: Figure 1 is a 50 front elevation, partly broken away, of a portion of one form of locket watch made in accordance with my invention; Fig. 2 is a sectional elevation taken on line $x-x$ of Fig. 1, looking toward the left in said figure; Fig. 55 3 is an elevation, in outline, of the back side of the watch represented in Figs. 1 and 2;

Fig. 4 is a sectional elevation, similar to Fig. 2, illustrating my improvements as embodied in a locket watch having the American system of setting; Fig. 5 is a detail section taken on line $y-y$ of Fig. 4; and Fig. 6 is a sectional elevation similar to Fig. 2, illustrating a modification.

Referring to the drawings, Figs. 1, 2 and 3 illustrate a locket watch case comprising a 65 bezel 2, a crystal 3 and a hinged back 4, which parts are of the usual construction, except as hereinafter described, and are adapted to receive either a lever-setting or a pin-setting watch movement, or a movement in 70 which the setting as well as the winding is done by manipulation of the winding stem only. 5 represents the upper end of the winding stem of such a movement, and inasmuch as watch movements and watch cases 75 are commonly made separately and combined as desired, I provide as an element of the case a terminal portion 6 which is rigidly secured to the upper end of the winding stem 5 when the movement is fitted to the case. 80 This terminal portion 6 is located within the rim of the watch case and terminates at its upper or outer end in an eye 7, and to this eye is preferably attached a link 8 by means of which the watch may be more readily sus- 85 pended on a neck chain or a chatelaine pin, or attached to a fob or the like. Said terminal portion 6 is rotatably mounted in the watch case, so as to serve as a means for rotating the stem 5 in winding the watch, and 90 in order to resist the outward pull on the winding stem when the watch is suspended said terminal portion is provided with an annular groove 9 which receives a rib 10 formed on an adjacent portion of the watch case and 95 preferably on the inner face of the back 4, as shown in Fig. 2, said rib 10 being provided by forming in the back 4 semi-circular de- 100 pressions 11 and 12 which are located upon opposite sides of the rib 10 and receive re- 105 spectively the cylindrical upper and lower portions 13 and 14 of the terminal portion 6. The bezel 2 is also provided with a semi-circular depression or recess 15 which is com- 110 mon to both of the portions 13 and 14 and co-operates with the depressions 11 and 12 to provide a bearing which incloses the terminal portion 6 and within which the latter is adapted to rotate.

In case the movement employed with this 115 form of case is of that type in which the setting is done wholly by means of the winding

stem, it is necessary that the stem be moved longitudinally before the setting operation is performed, and this is provided for by the construction illustrated in Fig. 2, since by 5 opening the back 4 the rib 10 is removed from the groove 9 in the terminal portion 6 and thus leaves the latter free to be given the necessary longitudinal movement. After the setting operation has been performed the 10 terminal portion and winding stem are pushed back into the position shown in Fig. 2 and the back of the watch is snapped into place, thereby locking the terminal portion and stem against outward movement but 15 leaving them free to be turned in winding the watch. In case a lever-setting or pin-setting movement is employed it is not necessary to open the back of the watch in order to set the same, but with either form of movement 20 the rib 10, by engaging the lower portion 14 of the terminal portion 6, resists under normal conditions any outward pull which may be applied to the terminal portion and thus removes any strain, due to such a pull, from 25 those parts of the watch movement with which the stem is operatively connected.

The outline of the watch, when suspended with its back outermost, is shown in Fig. 3, from which it may be seen that the appearance 30 of the watch is indistinguishable from that of a locket, in that the characteristic features found at the upper portion of an ordinary watch, namely, the pendant, crown and bow, are entirely omitted, the only visible 35 suspending means being the eye 7 which is provided at the upper end of the terminal portion of the winding stem, and the link 8 which is secured thereto.

Instead of forming an annular groove in 40 the terminal portion of the winding stem an annular rib 16 may be slipped over and secured to the terminal portion 6^a as shown in Fig. 6, in which case the bezel and back of the watch will be provided with corresponding 45 annular grooves 17 and 18 for the reception of said rib. This arrangement is applicable to such movements as employ a lever or a pin for throwing the stem into setting relation, and may be adapted to a stem-setting 50 movement by extending the annular groove 17 upwardly to a sufficient extent to permit the necessary longitudinal movement of the terminal portion 6^a and its rib 16 after the back of the watch has been opened, as 55 indicated in dotted lines at 17^a in Fig. 6. In either case the engagement of the rib 16 with the groove in the back of the watch will resist any outward pull on the terminal portion when the watch case is closed, without 60 interfering with the rotational movement of the terminal portion whereby the watch is wound.

In Figs. 4 and 5 I have illustrated my invention as applied to a watch case adapted to 65 contain a movement embodying the Ameri-

can system of setting, in which figure 2' is the bezel, 3' the crystal, 4' the back, 5' the winding stem, 6' the terminal portion thereof, 7' the eye formed on the outer end of the same, 9' the annular groove in the terminal portion 6', 10' the rib on the back of the watch case which fits into said annular groove, and 11' the recess formed in the bezel which receives the terminal portion 6' and permits its longitudinal movement when the 70 back of the watch is open. The winding stem is fastened to the terminal portion 6' and projects through a thimble 19 which is screw-threaded to engage the sleeve 20, said sleeve being mounted to rotate in a bearing 75 formed in the center 21. 22 is the cap which engages the center 21. The parts 19, 20 and 21 are of the usual construction in this type of movement, except that instead of projecting outward beyond the rim of the watch 80 case they are located within the periphery of the same, as shown, so that the only parts of the winding and setting movement which project above the rim of the watch case are the eye 7' formed on the upper end of the 85 terminal portion 6' and the link attached thereto, as in the case of the other constructions illustrated. In this form of movement both winding and setting are accomplished by the stem 5', the winding being done when 90 the parts are in the relative positions illustrated in Fig. 4, and the setting being done by first opening the back 4', thus removing the rib 10' from the annular groove in the terminal portion 6', then pulling said terminal portion 6' and the winding stem outward 95 into setting position, and then rotating said stem and thereby operating the setting movement through the sleeve 20 in the usual manner, the terminal portion and the winding stem being then pushed inward to the winding position and locked therein by closing the back of the watch case as hereinbefore described.

It will be seen that in each of the different 110 arrangements above described the usual pendant, crown and bow are entirely omitted and the winding stem and its terminal portion are rigidly fastened together, forming, in effect, a single piece, means being provided in 115 each instance for resisting any outward pull or strain upon the winding stem, under normal conditions, without interfering with the rotation of the winding stem for winding the watch. These are characteristic features of 120 my invention, and may be embodied in various other forms and constructions than those which are specifically described herein, as will be evident.

I claim as my invention:

1. A stem-winding watch comprising a rotatable winding stem having at its upper end a terminal portion located entirely within the periphery of the watch case, and means carried by the upper end of the terminal por- 130

tion, adjacent to the periphery of the case, for suspending the watch.

2. A stem-winding watch comprising a rotatable winding stem having at its upper end a terminal portion located entirely within the periphery of the watch case, means carried by the upper end of said terminal portion, adjacent to the periphery of the case, for suspending the watch, and means carried 10 by the watch case for resisting the outward pull on the winding stem when the watch is suspended.

3. A stem-winding watch having no pendant, bow or crown and comprising a rotatable winding stem, means for suspending the watch therefrom, and means operative with the opening and closing of the watch case for permitting and preventing longitudinal movement of said stem.

20 4. A stem-winding watch comprising a winding stem, a terminal portion secured to said stem and mounted to rotate in the case of the watch, said terminal portion being located entirely within the periphery of the 25 watch case and provided with means for suspending the watch therefrom, and means for resisting the outward pull on said stem when the watch is suspended.

5. A stem-winding watch comprising a 30 winding stem, a terminal portion secured to said stem and mounted to rotate in the case of the watch, said terminal portion being provided with means for suspending the watch therefrom, and means operative with 35 the opening and closing of the watch case for permitting and preventing longitudinal movement of said stem.

6. In a stem-winding watch, the combination with the case, of a winding stem terminal 40 rotatably mounted in the rim of said case, within the periphery thereof, one of said

parts having a projection adapted to enter a recess formed in the other of said parts, whereby longitudinal movement of said terminal is prevented, means carried by the 45 outer end of said terminal, adjacent to the periphery of the case, for suspending the watch, and a winding stem secured to said terminal.

7. In a stem-winding watch, the combination with the case, of a winding stem terminal having an eye at its outer end and rotatably mounted in the rim of said case, one of said parts having a projection adapted 50 to enter a recess formed in the other of said parts, whereby longitudinal movement of 55 said terminal is prevented, and a winding stem secured to said terminal.

8. In a stem-winding watch, the combination with the case, of a winding stem terminal having an eye at its outer end and rotatably mounted in the rim of said case, a link connected to said eye, a winding stem secured to said terminal, and means for resisting the outward pull on said terminal and 60 stem when the watch is suspended.

9. A stem-winding watch comprising a rotatable winding stem having at its upper end a terminal portion located in the rim portion of the case, within the periphery 70 thereof, means carried by the outer end of said terminal portion for suspending the watch, and means for locking said stem against longitudinal movement and for releasing the same when desired.

In testimony whereof, I have hereunto 75 subscribed my name this twentieth day of June, 1908.

HENRY W. MATALENE.
